COLLAR

Ashley J. Logan, Waterville, Maine, assignor to
 C. F. Hathaway Co., Waterville, Maine, a corporation of Maine

Application April 16, 1940, Serial No. 329,852

4 Claims. (Cl. 2—132)

The present invention relates to improvements in apparel collars and more particularly to stiffening means therefor.

The main object of my invention is to provide a collar either of the detachable type or of the type which is attached to the shirt, said collar having means which will prevent the free corners thereof from curling.

There are presently many collars having different types of anti-curling devices but these all have the defect of either, on the one hand, presenting a collar which is too stiff and consequently uncomfortable and unsightly, or on the other hand, of not adequately stiffening the collar.

Therefore another object of my invention is to provide a collar having stiffening means in which said collar assumes the most favorable resiliency. In obtaining this condition, I have found that numerous changes had to be made. For example, in my improved collar, the stiffening member is at an angle to the vertical edge of the collar, an intermediate ply is provided, and other changes are made, as will be set forth in the subsequent description.

Another object of my invention is to provide stiffening means for a collar which will in no way interfere with the appearance of the front face of the collar.

Another object of my invention is to provide a collar having pockets formed therein, adapted to receive stiffening members, said pockets forming an angle with the vertical edges of the collar.

Another object of my invention is to provide a collar having pockets formed therein adapted to receive and hold stiffening members, said pockets forming an angle with the vertical edges of said collar and the open end thereof terminating at a point below the fold line of said collar.

Other objects of my invention will be set forth in the following description and drawing, which illustrate a preferred embodiment thereof, it being understood that the above statement of the objects of my invention is intended generally to explain the same without limiting it in any manner.

Fig. 1 is a rear view of a shirt in open position, partially broken away, showing my improved collar in turned up position and partially broken away.

Fig. 2 is an enlarged sectional view along line 2—2 of Fig. 1.

Fig. 3 is a sectional view along line 3—3 of Fig. 1.

Fig. 4 is an enlarged sectional view along line 4—4 of Fig. 1.

Fig. 5 is a fragmentary front view of the shirt in open position showing the collar turned up.

Referring to the drawing, B designates the body of a shirt having attached thereto in the usual manner a collar C. The collar C consists of a band or inner fold 2 and the top or outer fold 3, the said inner fold or band 2 being provided with the usual buttonhole 1 and button 4 at the free ends thereof.

The outer fold 3, with which the present invention is more particularly concerned, consists of a front ply 5, a rear ply 6, a lining 7 and intermediate plies 8. The front and rear plies 5 and 6 and the lining 7 are formed of pieces of fabric of substantially the same size and shape.

10 The top of rear ply 6 at each side thereof is bent inwardly to form the hems 9. Positioned between the lining 7 and rear ply 6 and at the outer ends of the outer fold 3, are the intermediate plies 8, each of said plies extending substantially one quarter the length of the fold.

15 The plies and the lining are sewn together along their lower and side edges by stitching 10 and the upper edge of said outer fold is sewn together and connected to the top of the inner fold by the row of stitches 11. It should be noted that the row of stitches 11 only passes through the middle of the top of rear ply member 6.

20 Running from the corners of the outer fold 3 and at an angle to the vertical edges 12 of said fold are the two pair of parallel stitches 13 joining the rear ply 6 and the intermediate plies 8, thus forming the diagonal pockets 14. Positioned in said pockets 14 are the resilient stiffening members 15 which run the entire length of the pocket, the lower ends of said members being shaped so as to coincide with the lower edge of the outer fold. These stiffening members 15 may be made of any suitable material such as Celluloid, etc.

25 It should be noted that the intermediate plies 8 terminate at about the point where the row of stitches 11 engages the rear ply 6. The reason for this is that the presence of too many plies at the fold line between the inner and outer folds presents a cumbersome construction.

30 While I have shown my improvement as applied to one particular shape of collar, it is quite apparent that my novel construction may be applied to any shape of collar.

35 In applying my construction I have provided

a collar having a stiffening ply, a stiffener receiving pocket having no free uncut edges and thereby requiring no buttonhole trimming, said pocket being at an angle to the side edge of the outer fold of the collar. I have found this construction inexpensive and giving the most satisfactory results.

I have shown a preferred embodiment of my invention but numerous alterations and omissions may be made without departing from the spirit thereof.

What I claim is:

1. A collar of the character described comprising a band portion and a front fold, said front fold being formed by a front ply, a lining adjacent said front ply and of the same shape as said front ply, a rear ply of substantially the same shape as the front ply but having the side top parts thereof folding inwardly forming a hem which makes an angle with the top edge of the front ply, a pair of intermediate plies positioned between the lining and the rear ply at the outer ends of said outer fold, each of said intermediate plies being about one quarter the length of the outer fold, the lower and side edges of said plies and lining being stitched together and a row of stitches passing through the top edges of the band, the lining, the front and intermediate plies and the central part of the top edge of the rear ply, a pair of parallel rows of stitches between the rear and intermediate plies, said rows of stitches terminating close to the lower corners of the outer fold and forming a pair of pockets adapted to receive stiffening members.

2. A collar of the character described comprising a band portion and an outer fold portion, said outer fold portion comprising a front ply, a rear

ply and an intermediate ply, the lower and side edges of said plies being stitched together, a row of stitches passing through the band, the front and intermediate plies and the central part of the top edge of the rear ply to leave free the upper end portions of the rear ply, a pair of parallel rows of stitches between the rear and intermediate plies adjacent each end of the outer fold portion, said rows of stitches terminating close to the lower corners of the outer fold and forming a pair of pockets adapted to receive stiffening members.

3. A collar of the character described comprising a band portion and an outer fold portion, said outer fold comprising a front ply, a rear ply and a pair of intermediate plies positioned between the front and rear plies at the outer ends of said outer fold, each of said intermediate plies extending substantially less than half of the length of the outer fold, the lower and outer side edges of said plies being stitched together and a row of stitches passing through the band, the front and intermediate plies and the central part of the top edge of the rear ply to leave free the upper end portions of the rear ply, and rows of stitches in the end portions of the outer fold through the rear and intermediate plies forming pockets to receive a stiffening member.

4. A collar as claimed in claim 3, in which the parallel rows of stitches in the end portions of the outer fold are disposed at an angle to the side edges of the outer fold, the pockets formed by said parallel rows of stitches being disposed at an angle to the adjacent side edge of said outer fold.

ASHLEY J. LOGAN.
